(57) **CLAIM**

The ornamental design for a tire, as shown and described.

DESCRIPTION

FIG. 1 is a perspective view of a tire showing my new design;

FIG. 2 is a front view thereof, the rear view being the same;
FIG. 3 is a top plan view thereof, the bottom view being the same;

FIG. 4 is a right side view thereof, the left side view being the same;

FIG. 5 is an enlarged cross-sectional view taken along line 5-5 in FIG. 2; and,

FIG. 6 is an enlarged view taken along lines 6-6 and 6'-6' in FIG. 2.

In the drawings, the broken lines showing portions of the sidewall and inner bead depict portions of the tire that form no part of the claimed design.
